UNITED STATES PATENT OFFICE.

PAUL PRIEM, OF HEIDENHEIM-ON-THE-BRENZ, GERMANY, ASSIGNOR TO THE FIRM OF J. M. VOITH MASCHINENFABRIK, OF HEIDENHEIM-ON-THE-BRENZ, WÜRTEMBERG, GERMANY.

MACHINE FOR MAKING PASTEBOARD.

SPECIFICATION forming part of Letters Patent No. 748,983, dated January 5, 1904.

Application filed September 8, 1903. Serial No. 172,216. (No model.)

To all whom it may concern:

Be it known that I, PAUL PRIEM, a citizen of the Empire of Germany, residing at Bahnhofstrasse 5, Heidenheim-on-the-Brenz, in the

5 Kingdom of Württemberg and Empire of Germany, have invented certain new and useful Improvements in Machines for Making Pasteboard, of which the following is a specification.

10 In the well-known machines for making pasteboard, in which a plurality of screen-cylinders are used one behind the other, a pasteboard of uniform thickness is obtained when all the different cylinders are used.

15 When by the same machine thinner pasteboard has to be made, the fibrous layers on the different cylinders have not to be taken off by the felt; but, according to the thickness required for the pasteboard, one or more

20 screen-cylinders must be cut out—that is to say, placed out of action. This was heretofore accomplished either by permitting these cylinders to run in empty tanks or by removing them entirely from their vats before the 25 machine was started. These methods, however, were objectionable, as they were connected with a considerable loss of time.

The object of this invention is to furnish a means for cutting out any desired number of 30 screen-cylinders, so that pasteboard of any desired thickness can be made in the simplest possible manner. This is accomplished by removing some of the screen-cylinders, by means of suitable gearings, away from the 35 felt. As these cylinders are usually located vertically below the course of the paper, the removing of the cylinders is preferably accomplished by a lowering of the same either in their vats or together with their vats. This 40 arrangement furnishes the additional advantage that single vats can be withdrawn with the cylinders in lateral direction without interrupting the operation of the pasteboard-machine. This is the more advantageous, as 45 in this manner any repairs or the introduction of reserve parts and the cleaning of the screen-cylinders which is necessary from time to time by means of steam or hot water for

removing the adhering gum and fibers from the screens and the cleaning of the vats can 50 be accomplished without interrupting the working of the machine.

In the accompanying drawings, Figure 1 represents a side elevation of a pasteboard-machine with one of the screen-cylinders and 55 its vat cut out—that is to say, lowered below the fiber-carrying felt. Fig. 2 is a side elevation of one of the cut-out or lowered screen-cylinders, drawn on a larger scale; and Fig. 3 is a plan view of Fig. 2.

60 Similar characters of reference indicate corresponding parts.

In the machine for making pasteboard shown in the drawings any one of the vats V is lowered or raised simultaneously with its 65 screen-cylinder by means of four screw-spindles 1, which are operated simultaneously by one or two cranks 5, the shafts of which are supported on the upright standards of the pasteboard-machine. The transmission of 70 motion from the crank to the spindle and from one spindle to the other spindle of the same vat is accomplished by means of a worm-gear 2, beveled gears 3, and cross-shafts 4. The vat V is thereby lowered simultaneously 75 with the screen-cylinder supported in the same. One of the screen-cylinders is shown in Fig. 1 in lowered position. The vats are supported by rollers 7 on rails 8, which are carried by the screw-spindles 1 and lowered 80 or raised by the same. When any one of the vats—as, for instance, the third one from the right-hand side of Fig. 1—is lowered, it can be moved laterally by the rollers 7 on the rails 8 clear of the standards of the machine, after 85 which when necessary the vat can be further transported by means of a movable crane or placed on a portable supporting-frame for repairs, &c.

In place of the mechanism for raising and 90 lowering the screen-cylinder for moving the same sidewise out of the machine any other mechanism for accomplishing the same result may be used—as, for instance, eccentrics and toggle-levers, guide-rods, &c.—while for 95 the lateral removal of the vats in place of the

rollers and rails special tracks may be used, which are placed below the vat, on which the same is lowered.

For replacing the vat, with its screen-cylinder, accurately in its proper position and for supporting the same in this position during the running of the machine inclined brackets 6 are employed, which project from the standards and against which inclined stops 9 at the upper ends of the vat abut. The lateral movement of the vats can also be readily accomplished in such cases, in which the screens are lowered within the vats and not with the same, as shown in the drawings.

15 The supply of pulp, the motion-transmitting mechanisms for the cylinders, &c., have to be so arranged and connected with the vats and screen-cylinders that the lowering and lateral removal of the vats and screen-

20 cylinders can be accomplished without any difficulty in disconnecting the parts.

Having thus described my invention, I claim as new and desire to secure by Letters Patent—

25 1. In a machine for making pasteboard provided with a plurality of screen-cylinders, the combination of the screen-cylinders, with mechanism for lowering or raising the same so that any one of the cylinders can be lowered below the pulp-carrying felt and raised up to the same, substantially as set forth.

30 2. In a machine for making pasteboard provided with a plurality of screen-cylinders, the combination, with the screen-cylinders

and vats, of mechanism for lowering or raising the cylinders and vats, substantially as set forth.

3. In a machine for making pasteboard provided with a plurality of screen-cylinders, the combination, with the screen-cylinders 40 and vats, of means for lowering or raising the same, and means for moving them in lateral direction out of the machine, substantially as set forth.

4. In a machine for making pasteboard 45 provided with a plurality of screen-cylinders, the combination, with the screen-cylinders and their vats, of means for lowering or raising the same, brackets on the supporting-standards of the machine, and stops on the 50 vats for arresting the screen-cylinders and vats when in raised position, substantially as set forth.

5. In a machine for making pasteboard provided with a plurality of screen-cylinders, 55 the combination, with the screen-cylinders and vats, of means for lowering and raising the same, rollers on the vats, and lateral guide-rails on the supporting-standards for moving the cylinders and vats laterally out 60 of the machine, substantially as set forth.

In testimony that I claim the foregoing as my invention I have signed my name in the presence of two subscribing witnesses.

PAUL PRIEM.
